UNITED STATES PATENT OFFICE.

LOUIS WOJIDKOW, OF BROOKLYN, NEW YORK.

DESIGN FOR A STAND FOR TEA-KETTLES.

SPECIFICATION forming part of Design No. 27,940, dated December 7, 1897.

Application filed October 20, 1897. Serial No. 655,856. Term of patent 3½ years.

To all whom it may concern:

Be it known that I, LOUIS WOJIDKOW, a citizen of the United States, residing at Brooklyn, county of Kings, and State of New York, 5 have invented and produced a new and original Design for a Stand for Tea-Kettles, of which the following is a specification, reference being had to the accompanying drawing, forming part thereof.

10 The drawing represents a perspective view of my new design for stands for tea-kettles.

As shown in the drawing, the leading or material feature of my design consists of a leaf-like or foliate centerpiece which connects the spread uprights of the supports.

15 A indicates the base of the stand, and B the supports, extending or rising from the base and being inclined outwardly from the same. Each support B consists of curved uprights

b b', spread outwardly at their lower ends or 20 feet, where they are connected with the base A, and outwardly at their upper ends, where they are connected by a W-shaped cross-bar C. Below the cross-bar C and connecting the uprights b b' is a leaf-like or foliate center- 25 piece D.

Having described my invention, what I claim as new, and desire to secure by Letters Patent, is—

The design for a stand for tea-kettles, substantially as herein shown and described.

In testimony that I claim the foregoing as my invention I have signed my name in presence of two subscribing witnesses.

LOUIS WOJIDKOW.
